UNITED STATES PATENT OFFICE

CORWILL JACKSON, OF CHICAGO, ILLINOIS

MOLDING APPARATUS

Application filed January 23, 1930. Serial No. 422,819.

My present invention is especially designed by me for use in practicing the method described and claimed in my application for Letters Patent filed January 10, 1929, Serial 5 No. 331,668, and more specifically to an apparatus in which the intensity of the vibrations may be varied throughout a wide range without varying the frequency and without stopping the vibrating unit.

10 The main objects of this invention are: First, to provide a molding apparatus which is highly efficient in the molding of concrete slabs and parts of varying thickness and aggregates in which various mixtures or colors are employed without objectionable commingling thereof.

15 Second, to provide a vibrating apparatus for the practice of the method of my application referred to in which the intensity of the vibrations may be varied through a wide range without varying the frequency thereof.

20 Third, to provide such a structure in which the intensity of the vibrations may be varied with the apparatus in operation.

25 Further objects, and objects relating to details and economies of my invention will definitely appear from the description to follow. The invention is defined in the claims.

30 A structure which embodies the features of my invention is clearly illustrated in the accompanying drawing, in which:

Fig. 1 is a transverse vertical section on a line corresponding to line 1—1 of Fig. 2 of an apparatus embodying the features of my invention.

35 Fig. 2 is a side elevation, the hanger supporting shafts being shown in section.

Fig. 3 is an inverted view of the vibrating motor and its support, the clamps being omitted and the motor housing being partially broken away.

40 Fig. 4 is a side elevation of another embodiment or adaptation of my improvements, the form being mounted on a table instead of suspended as shown in Figs. 1 and 2.

45 In the embodiment illustrated in Figs. 1 and 2 the form 1 is supported by flexible hangers 2 suspended from drums 3 substantially as shown in my application for Let-

ters Patent Serial No. 413,981, filed December 14, 1929. The details of the suspending means, other than that they are flexible, form no part of my present invention.

I provide means for vibrating the form 51 or mold and for varying the intensity of the vibrations without varying the rate of vibrations. The vibrating unit in the embodiment illustrated consists of a motor designated generally by the numeral 4 having an unbalancing weight 5 on its shaft 6.

56 The yoke-shaped support 7 is detachably secured to the form by means of the form engaging clamps 8 connected by the adjusting rod 9 having a crank 10 at one end. The motor is mounted on a flexible hanger 11 connected at one end to the arm 12 of the support and at the other end to a link 13 pivoted at 14 adjacent the arm 15 of the yoke. The adjusting screw 16 is pivoted to the outer end of the link at 17 and projects through the arm 15 to receive the adjusting nut 18 provided with a hand wheel 19.

61 Thus arranged the flexible motor hanger 11 may be tensioned, that is, tightened or 66 loosened, with the result that the intensity of the vibrations may be varied through a very wide range. The tightening of the member 11 increases the intensity of the vibrations and loosening it decreases the intensity of the 71 vibrations. This is of material advantage in molding building blocks and panels where there is a variation in the character of the aggregate employed in facing, or where colored facings are employed with uncolored body 76 portions. The vibrations may be accurately gauged so as to prevent displacement of the facing material into the body material as might result if the vibrations were too intense. It is, however, desirable to maintain a 81 high and uniform rate of vibration throughout the variation of the intensity of vibrations.

86 My improved molding apparatus is therefore very readily adapted to meet the particular conditions or material operated upon. It is especially desirable for use with flexible hangers for the mold but may be very advantageously used where the mold is placed upon a solid table or bed 20 as shown in the 91

- adaptation of Fig. 4. Otherwise the parts are substantially as illustrated in Figs. 1 to 3.
- I have not attempted to illustrate the same but it will be understood that the support 5 clamp might be engaged directly with the side of a wall, form or the like. Other adaptations will be readily understood by those skilled in the art to which my invention relates.
- 10 Having thus described my invention what I claim as new and desire to secure by Letters Patent is:
1. In a molding apparatus, the combination of flexible form hangers, a motor provided 15 with an unbalancing weight, a yoke-like support provided with means for detachably mounting on a form, a link pivotally mounted on said support adjacent one arm thereof, a flexible hanger for said motor connected at 20 its ends to the other arm of said support and to said link, an adjusting screw pivotally connected to the outer end of said link and disposed through the adjacent arm of said support, and an adjusting nut on said screw engaging said arm.
  - 25 2. In a molding apparatus, the combination of a motor provided with an unbalancing weight, a yoke-like support provided with form engaging means, a link pivotally mounted on said support adjacent one arm thereof, a flexible hanger for said motor connected at its ends to the other arm of said support and to said link, an adjusting screw pivotally connected to the outer end of said link and disposed through the adjacent arm of said support, and an adjusting nut on said screw engaging said arm.
  - 30 3. In a molding apparatus, the combination of flexible form hangers, a motor provided with an unbalancing weight, a support 35 provided with form engaging means, said support having a member adjustably mounted thereon, a flexible support for said motor connected at one end to said support and at the other end to said adjustable member thereon, and an adjusting screw for said adjustable member of said support.
  - 40 4. In a molding apparatus, the combination of a motor provided with an unbalancing weight, a support provided with form engaging means, said support having a member 45 adjustably mounted thereon, a flexible support for said motor connected at one end to said support and at the other end to said adjustable member thereon, and an adjusting screw for said adjustable member of said support.
  - 50 5. In an apparatus of the class described, the combination of a flexible form hanger, a support 55 provided with a form engaging clamp, a flexible motor hanger connected at its ends to said support, and a motor provided with an unbalancing weight mounted on said motor hanger intermediate its point of connection to said support.

6. In an apparatus of the class described, the combination of a support provided with a form engaging clamp, a flexible motor hanger connected at its ends to said support, the connection for one end being adjustable, and a motor provided with an unbalancing weight mounted on said motor hanger intermediate its point of connection to said support.

7. In an apparatus of the class described, the combination with a flexible form hanger, a motor provided with an unbalancing weight, a support adapted for mounting on a form, a flexible hanger for said motor mounted at its ends on said support, and means for tensioning said flexible motor hanger.

8. In an apparatus of the class described, the combination with a support provided with form engaging clamps, of a flexible hanger mounted on said support, means for adjusting the tension of said hanger, and a vibrating means mounted on said hanger intermediate its ends.

9. In an apparatus of the class described, the combination of a support provided with form engaging members and having a flexible vibrating unit hanger connected at its ends thereto, a vibrating unit mounted on said flexible hanger intermediate its ends, and means for varying the tension on said hanger while the vibrating unit is running.

10. In an apparatus of the class described, the combination with a support adapted for attachment to a form and provided with a flexible motor hanger supported at its ends, a motor provided with an unbalancing weight mounted on said hanger intermediate its ends, and screw means for varying the tension on said motor hanger.

11. In an apparatus of the class described, the combination with a support adapted for attachment to a form and provided with a flexible motor hanger supported at its ends, a motor provided with an unbalancing weight mounted on said hanger intermediate its ends, and means for varying the tension on said motor hanger.

12. In an apparatus of the class described, the combination with a support adapted for attachment to a form and provided with a flexible vibrating unit hanger supported at its ends, a vibrating unit mounted on said hanger intermediate its ends, and screw means for varying the tension on said hanger.

13. In an apparatus of the class described, the combination with a support adapted for attachment to a form and provided with a flexible hanger supported at its ends, a vibrating unit mounted on said hanger intermediate its ends, and means for varying the tension on said hanger while the vibrating unit is running.

In witness whereof I have hereunto set my hand.

CORWILL JACKSON.
